UNITED STATES PATENT OFFICE

ALBERT LAW, OF JACKSON HEIGHTS, NEW YORK

METHOD AND MOLD FOR CASTING HOLLOW METAL ARTICLES

Application filed February 27, 1929. Serial No. 342,968.

This invention relates essentially to a method and mold for casting hollow metal articles, particularly such as tubular pipe fittings, and it is designed to provide a duplex 5 pattern plate whereby the core composed of green sand is molded and the plate serves to impress the exterior of the relief portion of the pattern in the green sand contained in the drag and cope.

10 An object of the invention is to provide a plate with cavities on one side to form the core and protuberances or relief patterns located in the reverse side of the plate for impressing one half of the pattern in the sand 15 of the drag and the other half in the sand of the cope.

Another object of the invention is to provide a vent plate for impressing channels in the half section of the core after the sand is 20 poured and rammed into the cavities of the pattern plate.

Another object of the invention is to provide the pattern plate with arbors suspended in the cavities and locking means adapted 25 for withdrawal from the exterior of the plate after one half of the core is finished. In this arrangement the arbors, after the two sections of the core are formed, constitute supports whereby the core is floated or positioned 30 in spaced relation to the pattern impressed in the sand of the drag and cope.

Another object of the invention is the method of impressing one half of the pattern in the drag and the other half in the cope 35 by the use of a plate having protuberances or patterns in relief and then using the reverse cavity side of the plate to mold the two sections of the core.

The novel combinations of the invention 40 are more fully described in the following specification and claims, reference being made to the accompanying drawings in which:

Fig. 1 represents a plan view of a pattern 45 plate embodying this invention.

Fig. 2 is a side view of the same.

Fig. 3 is a section taken along the line 3—3 of Fig. 1.

Fig. 4 is a similar section taken along the 50 line 4—4 of Fig. 1.

Fig. 5 is a plan view of the core vent plate.

Fig. 6 is a side elevation of the same.

Fig. 7 is a side elevation showing the method of molding the drag.

Fig. 8 is an inverted plan view of the pattern plate showing the arbors keyed in the cavities.

Fig. 9 is a side elevation showing the method of molding the cope.

Fig. 10 is a detail section taken along the 60 line 10—10 of Fig. 8.

Fig. 11 shows the flask prepared for casting.

As indicated in Figs. 1 to 4, the numeral 5 designates a pattern plate which is provided with protuberances 6 at the top and cavities 65 7 at the bottom of the plate, it also has portion 6^a to form core prints. The plate also has lateral flanges 8 made to form hand-grips for actuating the plate and ears 9 each with a hole 10 serve to align the plate on an object, as hereinafter described.

In Figs. 5 and 6 is shown a vent plate 11 having longitudinal and transverse ribs 12 and it has side flanges 14 for manipulating 75 the plate. The configuration of the ribs can be varied depending on the shape of the article to be cast. The core vent plate is furnished with a plurality of ears 15 each having a pin 16 for engagement with the holes in the ears of the pattern plate. A drag 17 having similar ears 18 to coact with the pins 16 is arranged over the pattern plate, as shown in Fig. 7.

As indicated in Fig. 8, the cavities have 80 suspended therein arbors 19 supported on notched shoulders 20 formed in the wall of the cavity. These arbors extend longitudinally and transversely, but the arrangement can be changed to suit different shaped cores. A locking key 21 with a handle 22 extends 85 inwardly through a bore in the plate 5 and it has a bevelled end 24 best seen in Fig. 10 to contact with the face of the arbor so as to prevent the arbors from dropping out when the plate is reversed.

In Fig. 9 is shown a cope 25 having ears 26 with a pin 27 fixed to each ear in order to align the cope with the pattern plate or with 90 the drag.

The method of molding the core and making the impressions of the pattern in the sand of the drag and cope is as follows:—

Place the pattern plate having the arbors positioned in the cavity with its core side up, ram up the core side of the plate pattern and strike off the sand. Place the core vent plate with its ribs against the core face of the pattern and reverse to the position shown in Fig. 7. The drag 17 is then slid onto the pattern plate, the relief pattern being on top, ram the sand in the drag then lift off and set aside. The half of the core and the pattern is then formed by lifting off the pattern plate and leaving the core resting on the core vent plate, then take the drag half of the flask and position it over the core which rests on the core vent plate, reverse and then remove the core vent plate, and the drag half of the mold is complete. Insert the pins on the ears of the cope through the holes in the ears of the pattern plate with its core side up, as indicated in Fig. 9, set the locking pins for the arbors, ram up and strike off the surplus sand, reverse and place the upper half of the core on top of the drag thereby completing the entire core. Ram up the sand in the cope with the relief of the plate on top, strike off and punch a sprue hole 28 through the sand to communicate with the space 29 between the face of the core and the surface of the patterns impressed in the sand of the cope and drag. Close cope over drag and mold is completed as indicated in Fig. 11. It will be obvious that the ribs on the plate 11 will impress channels 12' in the core suitable for the escape of the gases generated during the molding of the article.

I claim:—

1. An apparatus for forming a mold in which to cast hollow metal articles comprising a plate with protuberant patterns in relief on one side for impressing in the sand contained in a flask one portion of a mold, said plate having a cavity in the reverse side whereby a portion of the core is produced.

2. An apparatus for forming a mold in which to cast hollow metal articles comprising a plate with protuberant patterns in relief on one side for impressing in the sand contained in the flask one portion of a mold, said plate having a cavity in the reverse side whereby a portion of the core is produced and a plate adapted to cooperate with said pattern plate having means thereon to form vents in the core.

3. An apparatus for forming a mold in which to cast hollow metal articles comprising a plate with protuberant patterns in relief on one side for impressing in the sand contained in the flask one portion of a mold, said plate having a cavity in its reverse side for producing a portion of a core, bores located in the wall of the cavity, means located in the cavity wall for supporting an

arbor, and locking means extending through said bores coacting with the arbor to prevent it from dropping out of the cavity when reversing the plate.

4. The method of forming a mold for casting hollow metal articles which consists in taking a plate provided with patterns in relief on one side and cavities in the reverse side with cavity side uppermost, said cavities having arbors therein, filling the cavities with sand, placing a core vent plate over the cavity side of the pattern plate, reversing both pattern and vent plates, placing the drag over the relief side of the pattern plate, filling the drag with sand, lifting off the drag, removing the pattern plate, positioning the drag over the half core resting on the vent plate, reversing the drag and vent plate and removing the vent plate thereby completing one-half of a mold with a half core lying therein, then taking said pattern plate with cavity side uppermost and having core arbors locked therein and filling the cavities with sand and placing it over the aforesaid half of the finished mold, releasing the locking device, lifting off the pattern plate, taking the pattern plate with relief side up, placing the cope over said plate and filling it with sand, removing the cope from the pattern plate and positioning the cope over the finished half mold thereby completing the entire mold.

5. The method of forming the drag-half of a mold for casting hollow metal articles which consists in taking a plate provided with patterns in relief on one side and cavities in the reverse side with the cavity side uppermost, placing arbors in the cavities, filling the cavities with sand, placing a core vent plate with vent forming ribs therein over the cavity side of the pattern plate, reversing both the pattern plate and vent plate to bring the relief side of the pattern plate uppermost, placing the drag over the relief side of the pattern plate, filling up the drag with sand, lifting off and setting aside the drag, lifting off the pattern plate leaving one-half of the core resting on the vent plate, positioning the drag over the half core resting on the vent plate, reversing the mold, removing the vent plate whereby one-half of a mold with a half core lying therein is completed.

6. The method of forming the cope part of a mold for casting hollow metal articles which consists in using a plate with patterns and corresponding cavities with the cavity side uppermost, placing and locking arbors in the cavities, filling the cavities with sand, reversing the plate with cavity side down and placing it over the finished drag part of a mold, releasing the locking device, lifting off the pattern plate whereby the upper half of the core lies on the lower half of the core, taking the pattern plate with the relief side

up, placing the cope over said plate, filling it with sand, punching a sprue hole through the cope, removing the cope from the pattern plate, positioning the cope over the finished drag mold thus forming a complete mold.

5 In testimony whereof I have hereunto set my hand.

ALBERT LAW.
